UNITED STATES PATENT OFFICE

145,948

DESIGN FOR A DESK

Karl O. Larson, Minneapolis, Minn.

Application March 3, 1945, Serial No. 118,245

Term of patent 14 years

(Cl. D33—7)

To all whom it may concern:

Be it known that I, Karl O. Larson, a citizen of the United States, residing at Minneapolis, in the county of Hennepin and State of Minnesota, have invented a new, original, and ornamental Design for a Desk, of which the following is a specification, reference being had to the accompanying drawing, forming part thereof.

The single figure in the drawing is a perspective view of a desk showing my new design.

The other side of the desk body from that shown in the drawing is flat and identical with the side shown. The outer end of the desk body is also flat and identical with the inner side shown in the drawing.

I claim:

The ornamental design for a desk, as shown and described.

KARL O. LARSON.
